CLAIM

I claim the ornamental design for a cooling vest, as shown and described.

DESCRIPTION

A portion of the disclosure of this patent document contains material to which a claim for copyright is made. The copyright owner has no objection to the reproduction of the patent document or the patent disclosure, as it appears in the U.S. Patent Office records, but reserves all other copyright rights whatsoever.

FIG. 1 is a front view of a first embodiment of a cooling vest according to my design;

FIG. 2 is a rear view of the cooling vest of FIG. 1;

FIG. 3 is a front perspective view of the cooling vest of FIG. 1;

FIG. 4 is a rear perspective view of the cooling vest of FIG. 1;

FIG. 5 is right side view of the cooling vest of FIG. 1;

FIG. 6 is left side view of the cooling vest of FIG. 1;

FIG. 7 is a partial view illustrating the profile taken through the line 7-7 as shown in FIG. 5;

FIG. 8 is a partial view illustrating the profile taken through the line 8-8 as shown in FIG. 5;

FIG. 9 is a partial view illustrating the profile taken through the line 9-9 as shown in FIG. 1;

FIG. 10 is a partial view illustrating the profile taken through the line 10-10 as shown in FIG. 1;

FIG. 11 is a front view of a second embodiment of a cooling vest according to my design;

FIG. 12 is a rear view of the cooling vest of FIG. 11;

FIG. 13 is a right side view of the cooling vest of FIG. 11;

FIG. 14 is a left side view of the cooling vest of FIG. 11;

FIG. 15 is a partial view illustrating the profile taken through the line 15-15 as shown in FIG. 11;

FIG. 16 is a partial view illustrating the profile taken through the line 16-16 as shown in FIG. 11;

FIG. 17 is a partial view illustrating the profile taken through the line 17-17 as shown in FIG. 13; and,

FIG. 18 is a partial view illustrating the profile taken through the line 18-18 as shown in FIG. 13.

The broken lines in the drawings illustrate portion of the cooling vest which form no part of the claimed design.

1 Claim, 18 Drawing Sheets
